UNITED STATES PATENT OFFICE.

HARRY F. BURK AND GUSTAF W. GUSTAFSON, OF BURLINGTON, IOWA.

MOVING-PICTURE MACHINE.

Application filed November 14, 1923. Serial No. 674,693.

To all whom it may concern:

Be it known that we, HARRY F. BURK and GUSTAF W. GUSTAFSON, citizens of the United States, residing at Burlington, in the county of Des Moines and State of Iowa, have invented certain new and useful Improvements in Moving-Picture Machines, of which the following is a specification:

This invention relates to a moving picture machine more particularly to the shutter and the object of our invention is to gain greater percentage of light without producing the flicker in the picture which heretofore has been eliminated at the sacrifice of a more intense light.

Another object of our invention is to use as small a blade as possible with exact amount of current being used relative to a certain speed of the machine.

Another object of our invention is to arrange an automatic blade which is governed by the speed of the shutter, the resistance of the blade to the air determining its position.

In the accompanying drawings:

Figure 1 is a plan view of the shutter;

Fig. 2 is a transverse section of the shutter;

Fig. 3 is a rear plan view of the shutter;

Fig. 4 is a detail perspective view of one of the blades; and

Fig. 5 is an enlarged transverse section through the hub of the shutter.

The numeral 1 indicates an annular rim to which is attached a segmental blade 2, which terminates centrally of the rim and is provided with a hub 3. Secured to the opposite sides of the hub of the blade 2 are washers 4 and 5. The numeral 6 indicates a segmental blade, the hub of which has an opening of sufficient diameter to receive the washer 5. The outer end of this blade 6 is received in an annular groove 7 in the rim 1, the blade being adjustable within the annular groove 7, the blade being of such a thickness as to be adjustable manually in the groove and remain in its adjusted position. The numeral 8 indicates a supporting rib integral with the

rim 1 adapted to extend inwardly to the center of the rim and is provided with a hub 9 to which is attached the bearing 10 of the shutter. Arranged upon the blade 2 is a movable blade 11 rotatably mounted upon the washer 4, bolts 12 passing through suitable openings in the hub 9 integral with

the member 8, thence through the blade 2 and the washers 4 and 5 arranged on the opposite side of the blade receiving nuts which secure the several parts together, the bolts 12 receiving upon the outer ends thereof a washer 13 spaced from the blade 11 and a spiral spring 14 is adapted to pass around the screw bolts 12. One end of this spring is secured to the blade 11 and the opposite end 15 engages one edge of the blade 6. This blade 11 is provided with deflector wings 16 which as the shutter is rotated offer a certain resistance to the air against the tension of the spring 14. In this manner the blade 11 is moved to or from the member 6. The spring 14 tends to move the blade in a counter clock-wise direction, the shutter being adapted to move in a clock-wise direction.

As stated, the blade 6 is manually adjustable in the initial starting of the shutter. Should there be any flicker on the screen it could be overcome by either moving the blade 6 toward blade 2 or blade 11. Generally it is plausible to move it toward blade 2. This blade 6 is set to operate correctly on any amperage or speed from 100 amps. down to 20 or 25 and from 100 revolutions per minute to 65 revolutions. When the blade 6 is set by the operator it will hardly need be set again as he uses nearly the same amperage all the time but it may be changed to a larger amperage if desired. Should any flicker occur, blade 6 can be moved toward the left to the blade 2. If no flicker appears this blade 6 should be moved to the right toward blade 11 until a bit of flicker appears. Then move blade 6 toward the left toward blade 2 about one sixteenth of an inch and it will be exact because blade 11 working as a governor with fan blades, makes the blades come together as the machine runs faster, and spread apart the blades 6 and 11 when the machine runs slower. In this manner the inclination of the machine to flicker is automatically eliminated according to the speed of the machine.

We claim:

1. A shutter adapted to be mounted upon a shaft, consisting of an annular rim, a fixed blade carried by said rim provided with a hub centrally of said rim, a blade movable about its axis mounted upon the hub of the first mentioned blade, a blade movable about its axis mounted on the op-

- posite side of the hub of the first mentioned blade provided with air deflectors and a tension spring secured to said blade adapted to resist the action of said air deflectors.
6. 2. A shutter adapted to be mounted on a shaft consisting of an annular rim, a segmental blade integral therewith extending inwardly from the rim and provided with a hub having a plurality of annular grooves, 10 a blade movable about its axis mounted in one of said grooves, the outer end of which is received in an annular groove in said rim, an auxiliary movable blade mounted in the other of said grooves of the hub, a tension spring carried by the last mentioned blade and contacting with the first mentioned movable blade and air deflectors carried by the last mentioned blade for effecting a movement of the last mentioned blade 15 relative to the first mentioned blade.
3. The combination with a rotary shaft of a moving picture machine, a bushing mounted upon said shaft, a fixed blade secured to said bushing, an annular rim 20 mounted upon the outer periphery of said fixed blade, said rim being provided with an annular groove, washers secured to either side of the hub of said fixed blade, a movable blade mounted upon one of said washers, its outer end received in said annular groove of the rim and capable of adjustment and a rotatable blade mounted upon the opposite washers of said first mentioned blade, a spring secured to said last mentioned 25 blade, the opposite end of which engages
- the second mentioned blade and air deflectors arranged on the last mentioned blades whereby the last mentioned blade is moved relative to the other blades as the shutter is rotated. 40
4. A shutter adapted to be mounted upon a shaft, comprising a bushing keyed to said shaft, a fixed blade secured to said bushing, an annular rim secured to the periphery of said fixed blade, a plurality of 45 movable blades carried by said fixed blade, an annular groove in said rim adapted to receive the outer end of said movable blade, a movable blade mounted for rotation upon said fixed blade and provided with diametri- 50 cally opposite air deflectors and a spring attached to the last named movable blade adapted to resist the action of said air deflectors when the shutter is rotated.
5. A shutter adapted to be mounted upon 55 a shaft consisting of an annular rim, a hub supported from said rim concentrically therewith, a fixed blade carried by said rim, a blade movable about its axis mounted upon said hub, a second axially movable blade 60 carried by said hub and provided with air deflectors, and a tension spring secured to said blade and contacting with the first-mentioned movable blade for effecting a movement of the last-mentioned blade relative to the first-mentioned blade. 65

In testimony whereof we affix our signatures.

HARRY F. BURK.
GUSTAF W. GUSTAFSON.
